C. W. HARROLD

INKING MECHANISM

Filed May 27, 1919

BY

Charles W. Harrold.
Philip C. Keck

ATTORNEY

UNITED STATES PATENT OFFICE.

CHARLES W. HARROLD, OF CLEVELAND, OHIO, ASSIGNOR TO THE HARRIS AUTOMATIC PRESS COMPANY, OF CLEVELAND, OHIO, A CORPORATION OF OHIO.

INKING MECHANISM.

Application filed May 27, 1919. Serial No. 300,093.

To all whom it may concern:

Be it known that I, CHARLES W. HARROLD, a citizen of the United States, and a resident of the city of Cleveland, in the county of 5 Cuyahoga and State of Ohio, have invented certain new and useful Improvements in Inking Mechanisms, of which the following is a specification, reference being made to the accompanying drawings, forming a part 10 thereof.

My invention relates to inking mechanisms for printing and lithographing presses and other similar machines, and the objects of my invention are, among other things, to 15 provide a novel inking mechanism which is simple in its construction, positively controlled and actuated in its operation, and which will distribute and apply the ink uniformly without forming films of ink of irregular thicknesses on the inking rolls, more particularly on the ductor roll as the ink is applied thereto from the fountain roll. In printing machines utilizing roller inking mechanisms such fountain roll is usually in- 20 25 30 35 40 45 50 55 60 65 70 75 80 85 90 95 100

termittently rotated by any suitable driving device connected with the press itself, the extent of its rotation in any cycle of operation being adjustable according to the quantity of ink required for any particular job, and a particular object of my invention is to provide means whereby the fountain roll and ductor roll may be positively rotated in unison and at the same speed when the former is rotated, instead of allowing the ductor roll to be rotated solely by its frictional contact with the fountain roll which method of operation is likely to cause slipping and piling up of the ink on the surface of the ductor roll. A further object of my invention is to provide means whereby the ductor roll may be positively controlled and driven both by the ink drum or distributing rollers and also by the fountain roll acting alternately, so that the ductor roll may at all times be not only under direct control but also be positively actuated during the inking distribution between the various inking rollers.

Further objects and advantages will appear hereinafter and be particularly pointed out in the claims, and I have shown a pre-

ferred embodiment of my invention in the accompanying drawings in which—

Figure 1 is a top plan view of my improved inking mechanism, the fountain-roll 55 actuating mechanism being omitted;

Figure 2 is an end view looking in the direction of the arrow in Figure 1;

Figure 3 is a side elevation, partly in section, illustrating a method of mounting the 60 friction disk to coact with the shiftable inking drum; and

Figure 4 is a diagrammatic view illustrating the disks at the ends of the ductor and fountain rolls. 65

Similar numerals refer to similar parts through the several figures.

Referring to Figures 1 and 2 of the drawings, the frame work 9 of the press supports the ink fountain 10 which holds the ink to 70 be applied to the fountain roll 11 mounted on the shaft 12 which is suitably journalled in the frame 9. On one end of the shaft 12 the ratchet 13 is affixed and to this shaft the rock arm 14 carrying the pawl 15 is journalled, the pawl 15 being adapted to coact with the ratchet 13. The arm 14 is intermittently rocked on the shaft 12 by the link 16 which is reciprocated from any suitable source of power connected with the press and 80 is not shown. By this mechanism the fountain roll 11 is intermittently rotated in the direction of the arrows shown in Figure 2.

The ductor roll 17 mounted on the shaft 18 is adapted to receive the supply of ink 85 from the fountain roll 11 and thereafter transfers same to the surface of the revolving inking drum or distributing rollers to be thereafter carried and applied to the printing plate or type of the press. The 90 ends of the shaft 18 are carried by the forked ends 19 of the rock arms 20 affixed to the rock shaft 21 pivoted in the frame 9; Likewise affixed to the shaft 21 is the arm 22 carrying at its extremity the cam-roller 23 95 adapted to coact with the cam 24 mounted on the shaft 25 which carries the inking drum 26. The shaft 25 is journalled in the frame 9 and is driven in any suitable manner (not shown). The cam 24 is so arranged 100 on the shaft 25 that the cam-roller 23 bears upon the high part of the cam 24, thereby

pressing the ductor roller 17 against the fountain roll 11 during the period when the pawl and ratchet drive for the fountain roll 11 is acting to rotate such fountain roll 11, 5 the rolls 11 and 17 being in surface-to-surface contact when the fountain roll 11 is rotated.

In Figures 1, 2, 3 and 4 I have shown the form of my inking mechanism in which it 10 is advantageous and desirable to drive the ductor roll 17 in unison with the inking drum 26 when both are in operative contact as shown in Figure 2, to the end that the ductor roll 17 may be at all times in the cycle of 15 operation positively driven and also under positive control from the motive power of the press when it is either receiving or distributing the ink as hereinbefore described, that is to say, in one part of the cycle the ductor roll 17 is positively actuated and controlled by the mechanism which drives the fountain roll 11, and in another stage in the cycle of 20 operation this ductor roll is positively actuated and controlled by the more rapidly revolving inking drum 26. Referring to Figure 1, the fountain roll 11 has the female frictional disk member 35 secured thereto by a key as shown in Figure 4, such disk 35 consisting of yieldingly associated members, the 25 movable member being backed by the springs 36 secured between the disk 35 and the collar 37 secured to the shaft 12, as shown in Figure 1. The ductor roll 17 also has the male friction disk member 38 adapted to coact with the disk 35 on the fountain roll and also with the female friction disk member 39 slidingly mounted on the shaft 25 of the inking drum 26 so as to be held against lateral displacement whenever the inking drum 26 is shifted 30 slightly in a longitudinal direction in accordance with the best practice in printing presses, the disk 39 being held in the bracket 40 secured to the frame of the machine and is operatively connected to the shaft 25 by a 35 feather 42. In Figure 4, I have shown diagrammatically the two positions of the ductor roll risk 38; when the disk 38 on the ductor roller shaft 18 is in operative contact with the fountain roll disk 35, it is shown in dotted lines, but when the disk 38 contacts with the inking drum disk 39 it is shown in full lines.

It is obvious that other means of operatively connecting the ductor roll 17 with both 40 the fountain roll 11 and the inking drum 26 may be devised to the end that such ductor roll may be positively actuated and controlled by the particular roll with which it may be in frictional contact, but the foregoing construction in which a friction disk drive is utilized is a preferred embodiment of my invention chiefly because of the simplicity and efficiency of the coacting elements employed. In this invention heretofore described it has 45 been found in practice that the momentum of

the ductor roll 17 is not sufficient to cause rotation of the fountain roll 11 when they are brought into contact as the latter fits closely in its bearings at the ends of the fountain 10, and the friction of these end bearings and of the fountain blade is greater than the momentum of the ductor roll which has already slackened its rotative speed when it reaches contact with the fountain roll. There may be initially a slight relative movement 75 between the peripheral surfaces of these two rolls but the ductor roll 17 having previously transferred its ink to the ink drum 26 has only a very thin film of ink remaining on its surface. This thin film may 80 have a tendency to pile up slightly along the lower line of contact of the rolls, but the quantity is small and this is rolled or ironed out by the positive rolling contact of these two members on the next rotative movement 85 of the fountain roll 11; in other words such piled-up ink film is again distributed over the surface of the ductor roll 17 simultaneously with the new supply of ink from the fountain roll. 90

My invention, in its broadest aspects, is not limited to the particular constructions shown, nor to any particular constructions or arrangements of parts by which it has been, or may be, carried into effect, as many changes and alterations may be made in the structures shown without departing from the principles of the invention, and without sacrificing its chief advantages. 95

I claim as my invention:

1. In an inking mechanism, an intermittently rotatable fountain roll, an independently rotatable inking drum, said roll and drum rotating at different speeds, a ductor roll movable alternately into contact with said fountain roll and inking drum, and independent coacting means carried by said fountain roll, said inking drum and said ductor roll and directly controlled by the relative position of the ductor roll for driving same from either the fountain roll or the inking drum. 100

2. In an inking mechanism, an intermittently rotatable fountain roll, an independently rotatable inking drum, said roll and drum rotating at different speeds, a ductor roll movable alternately into contact with said fountain roll and inking drum, and independent coacting means carried by said fountain roll, said inking drum and said ductor roll and directly controlled by the relative position of the ductor roll for driving same in unison with either the fountain roll or the inking drum. 110

3. In an inking mechanism, an intermittently rotatable fountain roll, an independently rotatable inking drum, said roll and drum rotating at different speeds, a ductor roll movable alternately into contact with said fountain roll and inking drum, and in- 120

dependent coating means carried by said fountain roll, said inking drum and said ductor roll and directly controlled by the relative position of the ductor roll for driving same from either the fountain roll or the inking drum alternately when in operative contact, said means automatically releasing the ductor roll when moved out of operative contact with either fountain roll or inking drum.

10 4. In an inking mechanism, an intermittently rotatable fountain roll, an independently rotatable inking drum, said roll and drum rotating at different speeds, a ductor roll movable alternately into contact with said fountain roll and inking drum, and independent coating means carried by said fountain roll, said inking drum and said ductor roll and directly controlled by the relative position of the ductor roll for driving same in unison with either the fountain roll or the inking drum alternately when in

operative contact, said means automatically releasing the ductor roll when moved out of operative contact with either fountain roll 25 or inking drum.

5. In an inking mechanism, a bodily movable ductor roll and means separate from the peripheral surface of said roll and directly controlled by the movements of said 30 roll for frictionally driving same at different speeds in different positions in its cycle of operation.

6. In an inking mechanism, a bodily movable ductor roll and means separate from 35 the peripheral surface of said roll for driving same alternately at different speeds controlled by the movements of the roll.

7. In an inking mechanism, a bodily movable ductor roll and means separate from 40 the peripheral surface of said roll for frictionally driving same at different speeds in different positions in its cycle of operations.

CHARLES W. HARROLD.
